CHARLES H. ALLEN, OF SAVANNAH, GEORGIA, ASSIGNOR OF ONE-HALF
TO JULIAN DE BRUYN KOPS, OF SAVANNAH, GEORGIA.

STANDARD FOR LOGGING-CARS.

SPECIFICATION forming part of Letters Patent No. 786,708, dated April 4, 1905.

Application filed December 9, 1904. Serial No. 236,201.

To all whom it may concern:

Be it known that I, CHARLES H. ALLEN, a citizen of the United States, residing at Savannah, in the county of Chatham and State 5 of Georgia, have invented a new and useful Improvement in Standards for Logging-Cars, of which the following is a specification.

My invention is designed to provide a new and improved standard for logging-cars 10 which is to be arranged on the ends of the transverse bolsters of the car to prevent the logs from rolling off when in transit, but which is capable of adjustment to permit the easy loading or unloading of the logs.

15 Although intended primarily for logging purposes, the device is equally applicable to cars for handling heavy lumber, iron beams, &c.

It consists in the novel construction and arrangement of the adjustable standard, which 20 I will now proceed to describe with reference to the drawings, in which—

Figure 1 is a perspective view of the end of a car-bolster with the adjustable standard 25 mounted thereon and in elevated position. Fig. 2 is a side view of the same parts with the standard lowered to permit the loading or unloading of the logs onto the bolster, and Fig. 3 is a sectional detail of the locking 30 devices.

H is the end of the bolster of the car, and A is the adjustable standard mounted thereon. This standard consists of curved steel 35 side arms arranged on opposite sides of the bolster and connected by and made integral with a cross-piece at the upper end. The ends of the side arms are enlarged and perforated and connected by a bolt B to the bolster, so as to form a hinge-axis about which the 40 standard may swing to the elevated position shown in Fig. 1 or the depressed position shown in Fig. 2. The bolt B goes entirely through the bolster and secures both arms of the standard. The standard is provided with 45 a U-shaped prop-frame C, whose arms are pivotally connected by bolts or rivets D to the upper portions of the side arms of the standard, either on the inside or outside of the same. The lower portion of this upright

prop-frame finds an abutting support on a 50 beveled face at the end of the bolster, which beveled face is provided with a protecting-surface formed by a metal sleeve J inclosing the end of the bolster. Through this sleeve and through the end of the bolster is formed 55 an inclined hole G, (see Fig. 3,) which receives and gives free passage to a spring-seated locking-bolt E. The end of the bolster is bored to a larger diameter than the sleeve, so as to receive a rigid collar F on the locking-bolt 60 and a subjacent spring K, which holds up the locking-bolt and locks the prop-frame against slipping off. When the spring-seated locking-bolt is forced down, the prop-frame C can slide off the beveled surface of the sleeve J. 65 To avoid the necessity of forcing the locking-bolt all the way down, the lower surface of the prop-frame is beveled at L, so that it slips readily over the top of the locking-bolt even if the latter has not been forced down below 70 the beveled face of the sleeve. The hole in the bolster and sleeve goes all the way through, so that it clears itself of dirt and water.

On the cross-bar of the upper ends of the standard-arms are formed pointed lugs or 75 teeth L, which serve to catch and hold the upper end of the skid on which the logs are raised to or rolled down from the bolster in loading or unloading the car.

On each side of the end of the bolster is 80 formed a recess equal to the thickness of the arms of the prop-frame C and into which these arms drop when the standard is lowered, so that the arms of the standard lie flat against the sides of the bolster. 85

The operation of my improved standard is as follows: In loading the car the standard is dropped to its lowest position, as seen in Fig. 2, with the cross-bar of the standard-arms resting flat against the beveled end of the 90 bolster. The skids are then placed in inclined position, as shown by dotted lines in Fig. 2, the upper ends of the skids being held by the teeth or projections L, so that there is no danger of slipping off. The logs are 95 then rolled up on the skids and are loaded onto the bolsters of the car. The skids are then removed, and the prop-frame C is then

pulled outwardly and lifted, as indicated by the arrow in Fig. 2, and the inclined face of the bottom of the prop-frame is brought to a flat bearing on the iron-clad bevel face of the bolster behind the locking-bolt E, the locking-bolt yielding downwardly as the inclined face of the prop-frame passes over it and then springing up again to lock the frame. The lifting of the prop-frame has by the above action elevated the standard to the position shown in Fig. 1, where its elevation prevents the logs from rolling off the ends of the bolster. The standard is firmly maintained in elevated position by the prop-frame C, and this is in turn prevented from moving outwardly at its lower end by the locking-bolt, and the locking-bolt is prevented from dropping down by the tension of the spring, which presses up against the collar F. To unload the logs, the locking-bolt is depressed against the spring. Then the prop-frame is pulled outward and slides over the locking-bolt and off the bevel face of the bolster, and the standards then drop to the position shown in Fig. 2, while the prop-frame swings under the end of the bolster, leaving nothing to prevent the logs being rolled off.

Having thus described my invention, what I claim as new, and desire to secure by Letters Patent, is—

1. A car-standard having arms hinged to the bolster and a prop for holding it elevated, said prop being hinged at its upper end to the standard, as described.

2. A car-standard having arms adapted to be hinged to the bolster, an upright prop-frame hinged at the top to the outer end of the standard and adapted to rest on the bolster and a locking device for the prop-frame substantially as described.

3. A car-standard consisting of a frame with hinged arms combined with and embracing the bolster, a prop-frame hinged at its upper end to the upper end of the standard, the end of the bolster being beveled and

adapted to form a bearing for the standard when dropped thereon, and also for the prop-frame when elevated, substantially as described.

4. The combination with a car-bolster, of an adjustable car-standard having an elevating-prop hinged thereto at its upper end and a locking-bolt for the prop arranged in a hole in the end of the bolster, substantially as described.

5. A hinged car-standard having a supporting device and a spring locking device substantially as described.

6. A car-standard having a beveled-face prop and a spring-seated locking-bolt substantially as described.

7. A car-standard consisting of bent and hinged side arms connected at one end by a cross-piece, a swinging prop-frame hinged to the standard-arms, a car-bolster having a beveled end adapted to receive the prop-frame and a spring-actuated locking-bolt passing through the bolster and engaging with the prop-frame substantially as described.

8. A car-standard consisting of bent and hinged side arms connected at one end by a cross-piece, a swinging prop-frame hinged to the standard-arms, a bolster having beveled end to abut against and support the prop-frame when elevated and rabbeted sides to receive the sides of the prop-frame when down and a locking device for the prop-frame when in elevated position substantially as described.

9. A car-standard consisting of bent and hinged side arms connected by a cross-piece, a swinging prop-frame hinged to the standard, a car-bolster with beveled end and reinforcing-sleeve and a spring-seated locking-bolt extending through said bolster end and sleeve substantially as described.
